UNITED STATES PATENT OFFICE.

JOHN C. CLARK, OF ATLANTA, GEORGIA.

SCREEN OR SEPARATOR.

1,049,052.

Specification of Letters Patent. Patented Dec. 31, 1912.

Application filed April 19, 1912. Serial No. 691,926.

To all whom it may concern:

Be it known that I, JOHN C. CLARK, a citizen of the United States, residing at Atlanta, in the county of Fulton and State of Georgia, have invented certain new and useful Improvements in Screens or Separators, of which the following is a specification.

This invention relates to devices for screening or separating materials and more particularly to devices for screening pul-
10 verized materials.

The objects of the invention are to pro-
15 vide a screen or separator which is simple
in construction, durable and efficient in op-
eration.

The invention relates specifically to that
class of screens which are arranged on an in-
cline and vibrated by means of suitable in-
termittently acting hammer mechanisms
20 and the features of novelty will be appar-
ent from the following description taken in
connection with the accompanying draw-
ings, in which—

Figure 1 is a front view of a screen em-
bodying my invention, certain parts being
broken away to illustrate other parts; Fig.
2 is a longitudinal section on the line 2—2
of Fig. 1; Fig. 3 is an enlarged side eleva-
30 tion of one of the striking or hammer mech-
anisms; and Fig. 4 is a fragmentary trans-
verse section on the line 4—4 of Fig. 2.

In the drawings, 10 and 11 indicate up-
right members which have their lower ends
35 connected with the base members 12 and 13
respectively. The base members 12 and 13
are connected together near the uprights 10
and 11 by means of a cross-piece 14. The
uprights 10 and 11 carry at their upper end
40 one end of the inclined members 15, the
lower end of these members being connected
with the base members 12 and 13. Cleats 17
45 are secured along the lower edges of the
members 15 and have secured thereto the
bottom boards 18 and the removable bottom
section 19. The boards 18 and the remov-
able section 19 are preferably covered on
50 their upper side with sheet metal so as to
form a durable wearing surface which will
also permit the material to slide freely
therealong. Cleats 20 are also secured on
the inner sides of the members 15 and co-
55 operate with the cross beams 21 and 22 to
support the screen 23. The screen 23 is se-
cured at its upper end along the under side
of a cross member 24 which is preferably se-
cured to the back 25 of the casing inclosing

the screens. The screen 23 has its lower end secured to a cross-piece 26 and is preferably provided with longitudinal extending reinforcing strips 27 and 28. Secured to the 60 members 15 above the cleats 20 are the members 29, along the top edge of which is secured the screen 30 which is preferably constructed with reinforcing strips 31 and 32 in the same manner as the screen 23. 65 The removable top plates 34 are supported on the upper edges of the members 15. The lower end of the casing inclosing the screens may be closed by a suitable cross-piece 35. The upper end of the screen 30 is secured to 70 the top of the member 24 and the lower end of said screen is secured to a cross member 36, which is preferably secured to the members 29.

At the top of the inclined frame for the 75 screens is a conveyer for the material to be screened. This conveyer may be of any de-
sired construction but I prefer to use and
have illustrated a conveyer which consists
of a box or casing 37 having an inlet 37', 80
and in which is a shaft 38. The shaft 38
carries a screw conveyer of the usual con-
struction. At the lower front corner of the
casing 37 is an opening 39 through which
the material may be discharged from the 85
casing 37 on to the screen 30. The opening
39 may be controlled by a sliding gate 40
which may be conveniently operated by
screw 41 having suitable hand-wheels 42.

Extending transversely of the screen cas- 90
ing below the screen 23 are shafts 43. I
have shown three such shafts but it will be
understood that I may use any number as
may be found desirable. These shafts are
supported in bearings 44, secured to the 95
members 15 and on the exterior thereof.
The shafts 43 have on one end thereof driv-
ing pulleys 45 which are engaged by a belt
46, the latter being driven by means of a
pulley 46' mounted on one end of the con- 100
veyer shaft 38; the opposite end of this shaft
being provided with a drive pulley 38'.
Idler pulleys 47 may be arranged adjacent
the pulleys 45 to increase the area of con-
tact of the belt 46 on the pulleys 45. The 105
shafts 43 carry plates 48 having lateral ex-
tensions 49 which are adapted to receive set
screws or pins 50. The set screws 50 engage
threaded openings in the extensions 49 and
are provided with lock nuts 52 whereby the 110
screws may be adjusted and securely held
in position.

On the under side of the screen 23 above the plates 48 are the plates 53. These plates are preferably secured to the reinforcing strips 27 and 28 and on the top of the strip 5 27 I arrange a plate 54 and secure this plate and the plate 53 in position by means of suitable bolts 55. The plates 53 are provided with inclined surfaces 56 which are adapted to be struck by the outer ends of the screws 10 50, as the shafts 43 rotate. This arrangement is clearly illustrated in Fig. 3.

The reinforcing strips 31 and 32 for the screen 30 are preferably arranged directly above the strips 27 and 28 for the screen 23 15 and on the under side of the strips 32 I secure the members 57 by means of suitable bolts 58. Set screws 59 have screw-threaded engagement with the members 57 and project above the reinforcing strip 31 and are 20 provided above the latter with locking nuts 60 which are adapted to hold the set screws in position. The lower ends of the screws 59 normally bear on the upper surface of the plates 54 so that when the members 53 are 25 struck by the screws 50 the force of the blow will be conveyed to the screen 30.

The operation of the mechanism is as follows: The material to be screened is fed into the inlet 37 of the conveyer casing 37 and 30 is conveyed through the casing 37 by means of the screw conveyer above described. The gate 40 being open to any suitable extent permits the material to fall from the casing 37 on to the screen 30. The screen 30 is 35 preferably much coarser than the screen 23 so that as the material moves downward on the screen 30 the smaller particles will fall through the meshes of the screen on to the screen 23. The rotation of the shafts 43 40 causes the set screws 50 to strike the inclined surfaces 56 on the members 53 and suddenly lift the screens with the material thereon. The suddenness of the blow struck by the screws 50 causes the finer particles of the 45 material to pass through the screens and also causes the coarser particles to be projected away from the screens and then fall back on to the same. When these particles again strike the screens they cause the finer particles to fall through the meshes. Each 50 time one of the screws 50 strikes an inclined surface 56, some of the fine material will fall through the screen and the blow of the coarser particles on the screen, due to their 55 falling onto the screen after being projected away from the latter, causes an additional quantity of the fine material to fall through the screen and therefore it will be seen that the machine will have a very large screening 60 capacity. The force of the blow struck by the screws 50 being conveyed to the screen 30 by means of the set screws 59, it will be seen that the screens 23 and 30 will be caused to vibrate in unison. The "fines" of the material screened will pass through both of the 65

screens and slide down the inclined bottom of the casing. The medium-sized particles will slide down along the screen 23 and off the bottom thereof, while the coarsest particles will slide down the screen 30 and off the bottom end of this screen. At the bottom of the casing suitable chutes or conveyors may be provided to carry away the separated materials.

It will be readily understood that by the 75 construction which I have devised for vibrating the screens the amplitude of the vibration is independent of the quantity of material on the screens and therefore the mechanism is highly efficient, even when the 80 material is fed to the screens too rapidly. By providing the adjustable set screws 50 and 59 I am able to closely regulate the action of the screen 30 and also vibrate both screens from a common vibrated mechanism. 85 The amplitude of the vibrations may be varied by adjusting the screws 50 and the rapidity of the blows may be varied by increasing or decreasing the number of screws carried by the plates 48 or by changing the 90 speed of the shafts 43. The force of the blows may also be varied by changing the speed of the shafts 43 and adjusting the screws 50.

It will be understood by those skilled in 95 the art that various changes may be made in the minor details of my invention within the scope of the claims and I therefore do not wish to be limited to the precise details of construction shown and described. 100

Having thus described my invention, what I claim is:—

1. In a machine of the class described, the combination of an inclined screen, means for rigidly supporting the screen at points 105 intermediate its ends, a striking plate arranged on the under side of said screen between said supports, a shaft arranged transversely of the machine below the screen, and continuously rotating means rigidly mounted on said shaft adapted to intermittently strike said plate.

2. In a machine of the class described, the combination of an inclined screen, means for rigidly supporting said screen intermediate 115 its ends, a shaft arranged below the screen, a striking plate on the under side of said screen, and adjustable means rigidly mounted on said shaft adapted to strike said striking plate.

3. In a machine of the class described, the combination of an inclined screen, a plurality of cross members adapted to rigidly support said screen intermediate its ends, a plate arranged on the under side of said screen and having a striking surface inclined relative to the latter, a shaft below said screen, a member rigidly mounted on said shaft, and a plurality of adjustable screws carried by said member and having 125 130

one end thereof adapted to strike said inclined surface when said shaft is rotated.

4. In a machine of the class described, the combination of a plurality of inclined screens arranged one above the other, a shaft arranged below the lower of said screens, a striking plate on the under side of the lower screen, a rigid spacing member secured to the upper screen and adapted to engage the upper side of the lower screen directly above said striking plate, and means on said shaft adapted to intermittently strike said striking plate when said shaft is rotated.

5. In a machine of the class described, the combination of a plurality of inclined screens arranged one above the other, means adapted to rigidly support the lower of said screens, a striking plate on the under side of the lower screen, an adjustable spacer secured to the upper screen and adapted to engage the upper surface of the lower screen directly above said striking plate, and means on said shaft adapted to strike said striking plate when said shaft is rotated.

25 6. In a machine of the class described, the combination of a plurality of inclined screens arranged one above the other, a plurality of cross members adapted to rigidly support the lower screen intermediate its ends, a striking plate secured to the under side of the lower screen between said cross pieces, a spacer secured to the upper screen and adapted to contact with the upper surface of the lower screen directly above said striking plate, and means carried by said shaft adapted to strike said striking plate when said shaft is rotated.

7. In a machine of the class described, the combination of a plurality of inclined screens arranged one above the other, a shaft arranged below the lower screen, a striking plate secured to the under side of the lower screen, an adjustable spacer secured to the upper screen and arranged to contact with the upper side of the lower screen directly above said striking plate, and a plurality of adjustable members rigidly mounted on said shaft and adapted to strike said striking plate when said shaft is rotated.

50 8. In a machine of the class described, the combination of a plurality of inclined screens arranged one above the other, a plurality of shafts arranged below the lower screen, a plurality of striking plates secured to the under side of the lower screen, a plu-

rality of spacers secured to the upper screen and arranged to engage the upper surface of the lower screen directly above said striking plates, and means carried by said shafts adapted to strike said striking plates.

60

9. In a machine of the class described, the combination of a plurality of inclined screens arranged one above the other, a plurality of members adapted to rigidly support the lower screen intermediate its ends, a plurality of shafts arranged below the lower screen, a plurality of striking plates secured to the under side of the lower screen, a plurality of adjustable spacers secured to the upper screen and arranged to contact with the upper surface of the lower screen directly above said striking plates, and means carried by said shaft adapted to strike said striking plates to vibrate both of said screens.

75

10. In a machine of the class described, the combination of a plurality of inclined screens arranged one above the other, a plurality of shafts arranged below the lower screen, a plurality of members arranged between said shafts and adapted to rigidly support the lower screen, striking plates secured to the under side of the lower screen, a plurality of spacers secured to the upper screen and adapted to contact with the upper surface of the lower screen directly above said striking plates, and means carried by said shafts and arranged to strike said striking plates when said shafts are rotated.

90

11. In a machine of the class described, the combination of a plurality of inclined screens arranged one above the other, a plurality of shafts arranged below the lower screen, a plurality of striking plates secured to the under side of the lower screen, adjustable spacing screws secured to the upper screen and having their lower ends arranged to contact with the upper side of the lower screen directly above said striking plate, and a plurality of adjustable members carried by each of said shafts arranged to strike said striking plates when said shafts are rotated.

95

In testimony whereof I affix my signature in presence of two witnesses.

JOHN C. CLARK.
